Primary Examiner — John Windmuller*Assistant Examiner* — Steven Czyz*(74) Attorney, Agent, or Firm* — Paul R. Martin(57) **CLAIM**

The ornamental design for a medication container, as shown and described.

DESCRIPTION

FIG. 1 is a perspective view of the medication carrier of our new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a right side elevational view thereof; and,

FIG. 7 is a left side elevational view thereof.
